UNITED STATES PATENT OFFICE.

LOUIS A. SWEM, OF BELLINGHAM, WASHINGTON.

SPARK-ARRESTER.

1,065,985.

Specification of Letters Patent.

Patented July 1, 1913.

Application filed May 9, 1911. Serial No. 626,049.

To all whom it may concern:

Be it known that I, LOUIS A. SWEM, a citizen of the United States of America, and a resident of the city of Bellingham, in the 5 county of Whatcom and State of Washington, have invented certain new and useful Improvements in Spark-Arresters, of which the following is a specification.

My invention has for a fundamental object, to provide a device of the above type 10 which will operate in an efficient manner to prevent the escape of sparks, cinders and unconsumed particles of fuel from the stack through the subjection of the smoke emanating from a furnace to the action of a 15 fluid sprayed or discharged into the same in a finely divided state.

A further object resides in the provision of novel means for promoting draft.

With the above and other objects in view, 20 to be referred to as my description progresses, my invention resides in the features of construction, arrangements and combinations of parts hereinafter described and succinctly defined in my annexed claims.

Referring to the accompanying drawing, wherein like numerals of reference indicate like parts throughout the several views: Figure 1 is a fragmentary vertical section 30 illustrating my invention, as in use. Fig. 2 is a top plan of my rotary fluid delivery means, and Fig. 3 is a section taken on line 3—3 of Fig. 1.

In referring to the drawing by numerals 35 of reference, 1 indicates a smoke stack, conveniently having its lower end portion enlarged, and in the form of a cylindrical section 2, and provided with an internal shoulder or interceptor 3 and a collector 4, said 40 interceptor and collector being arranged in vertical alinement and comprising inwardly projecting angular edge flanges of said section 2 and having their free edge portions turned toward one another and secured, as 45 by rivets as shown, to the lower edge of the upper or reduced section of stack 1 and to the flange 5, of a boiler 6, respectively.

Within the stack section 2, I provide fluid 50 delivery means comprising superimposed rotary jets 7, and 8, of the reactionary type, consisting of hollow heads having outwardly projecting nozzles 7', 8' respectively which are provided in their outer end portions with discharge orifices 9, arranged to discharge rearwardly relatively to the direction 55 of rotation of their respective jets,

which jets, as will be observed, are normally operated in opposite directions.

In practice, jets 7 and 8 are mounted for rotation on a hollow spindle 10 with their 60 heads in communication with suitable ports 10' thereof. Spindle 10 is connected at its opposite end portions with pipes 11 and 12 leading to suitable sources of steam and water respectively. Suitable valves, as 13, 65 14 and 15 are provided in pipes 11 and 12 and in a connecting branch 12' thereof, respectively.

Reference numeral 16 indicates a deflector 70 adjustably secured, as by a set screw 16' on spindle 10 beneath jets 7 and 8, for movement toward and from the latter, as may be desired for directing the smoke outwardly in an upward direction to the interceptor 3. In this connection, it will be observed that jet 7 has the free end portions 75 of its nozzles 7' turned upwardly to direct the fluid for discharge into stack 1 above interceptor 3, and thus, when operating as a spark arrester, said jet 7 will provide virtually a wall of fluid extending above and substantially parallel with the direction of deflection of the escaping products as effected by deflector 16.

Reference numeral 17 indicates a downwardly closing flap valve, arranged in spindle 10 intermediate jets 7 and 8, by which jet 8 is cut off from communication with pipe 11, while both of the jets can receive fluid from pipe 12. Thus, assuming 80 that the device is to be used as a blower, valves 14 and 15 are closed and valve 13 opened. Steam discharging from jet 7, is directed upwardly at a slight angle to the axis thereof, and thereby reacts to impart 85 rotary movement to the jet, as is well understood. Fan blades, as 18, are provided on jet 7, conveniently on the nozzles 7' thereof, to, act conjointly with the steam in the promotion of draft. During such operation 90 of the device, valve 15, can be opened as desired to admit water which will discharge through jet 8, valve 17 being held closed by the preponderance of pressure of the steam in the upper portion of spindle 10. With valves 13 and 14 closed and valve 15 open, water is admitted through pipe 12 to both jets which, as heretofore set forth, direct the water for discharge in opposite directions, jet 8 discharging substantially 95 horizontally over deflector 16 and collector 4, in which latter the fluid and intercepted

105

110

material precipitate, and jet 7 discharging upwardly into the upper portion of stack 1.

Having thus described my invention what I claim as new, and desire to secure by Letters Patent of the United States of America, is:

1. In a device of the type set forth, a conduit for the products of combustion, provided with an enlarged portion having in-turned substantially horizontally disposed concave upper and lower wall portions one overlying the other, means in said conduit for deflecting the products of combustion upwardly toward the upper concave wall portion of said conduit, and means for discharging fluid into the products of combustion at a point above said first means and said concave lower wall portions.
2. In a device of the type set forth, a conduit for the products of combustion provided with an enlarged portion having in-turned substantially horizontal concave upper and lower wall portions one overlying the other, means in said conduit above the lower concave wall portion thereof for deflecting the products of combustion upwardly toward the upper concave wall portion of said conduit, a hollow spindle in said conduit, means for supplying fluid to said spindle, and a jet rotatably mounted on said spindle in communication therewith for directing the fluid outwardly from said first means.
3. In a device of the type set forth, a conduit for the products of combustion, a hollow support in said conduit, a valve in said support, independent fluid discharge means supported by and communicating with said support on opposite sides of said valve, and independent fluid conducting means communicating with said support on opposite sides of said valve.
4. In a device of the type set forth, a conduit for the products of combustion, a hollow support in said conduit, independent fluid discharge means arranged one above the other on said support and communicating therewith, a valve in said support between said fluid discharge means, and independent fluid conducting means communicating with said support on opposite sides of said valve.
5. In a device of the type set forth, a conduit for the products of combustion, a hollow support in said conduit, independent fluid discharge means arranged one above the other on said support and communicating therewith, a valve in said support between said fluid discharge means, a supply pipe communicating with said support on one side of said valve, a second supply pipe

communicating with said support on the opposite side of said valve, valves in said supply pipes, a pipe connecting said first named pipes, and a valve in said last named pipe.

6. In a device of the type set forth, a conduit for the products of combustion having a portion of its length provided with an interceptor extending around its inner face, means in said conduit for deflecting the products of combustion toward said interceptor, means for directing fluid crosswise of said conduit intermediate the interceptor thereof and said first means, and other means for discharging fluid upwardly into said conduit above the interceptor thereof.

7. In a device of the type set forth, a conduit for the products of combustion having a portion of its length provided with an inwardly projecting interceptor, means in said conduit for deflecting the products of combustion toward the interceptor thereof, means for directing fluid crosswise of said conduit intermediate its interceptor and said first means, and other means arranged below the interceptor of said conduit for directing fluid upwardly into said conduit to a point above its interceptor.

8. In a device of the type set forth, a conduit for the products of combustion having a portion of its length provided with an interceptor extending around its inner face, means for deflecting the products of combustion toward the interceptor of said conduit, rotatable means for discharging fluid crosswise of said conduit above said first means, and a second rotatable means arranged below the interceptor of said conduit for directing fluid upwardly into said conduit above the interceptor thereof.

9. In a device of the type set forth, a conduit for the products of combustion having its lower portion provided on its inner face with an interceptor comprising a shoulder, a spindle in said conduit adapted to be connected with a source of fluid supply, rotatable fluid discharge means comprising a plurality of members arranged one above the other on said spindle in communication with the latter for delivery of fluid in outwardly diverging paths extending on opposite sides of the interceptor of said conduit, and an upwardly flaring deflector supported below said rotatable fluid discharge means for adjustment toward and from the same.

Signed at Bellingham, Wash. this 19th day of April 1911.

LOUIS A. SWEM.
